UNITED STATES PATENT OFFICE.

HARRY NAKAGAWA, OF TANANA, ALASKA.

FLOUR SIFTER.

Application filed March 26, 1923. Serial No. 627,863.

To all whom it may concern:

Be it known that I, HARRY NAKAGAWA, a citizen of the United States, residing at Tanana, in the Territory of Alaska, have invented new and useful Improvements in Flour Sifters, of which the following is a specification.

My present invention has to do with flour sifters of the type in which an agitator is oscillated above a concavo-convex screen through the medium of an oscillatory handle member connected with the shaft of the agitator.

The object of my said invention is to improve the type of flour sifter indicated by the provision of a simple and inexpensive construction which is, at once strong and durable and reliable and free from delicate parts such as are likely to get out of order after a short period of use.

To the attainment of the foregoing, the invention consists in the improvement as hereinafter described and definitely claimed.

In the accompanying drawings, forming part of this specification:—

Figure 1 is a top plan view of my novel sifter.

Figure 2 is a side elevation of the same with a portion of the body broken away.

Figure 3 is a detail rear end elevation of the handle members.

Figure 4 is a cross-section taken through the handle members and the agitator shaft in the plane indicated by the line 4—4 of Figure 1.

Figure 5 is a detail cross section showing the arrangement of the spring.

Similar numerals of reference designate corresponding parts in all of the views of the drawings.

Among other elements my novel sifter comprises a cylindrical body 1 open at its opposite ends. Appropriately fixed in the said body 1 at an intermediate point in the length thereof is a concavo-convex screen 2 of reticulated material. Movable to and fro immediately above the concave side of the screen 2 is an oscillatory agitator 3 which without affecting my invention may have any desired number of blades. The said agitator 3 is appropriately arranged relative to a shaft 4 so as to assure a strong engagement of the agitator with the shaft and the turning of the former in concert with turning of the latter. The shaft 4 is extended a considerable distance beyond the

body 1 and in a radial direction from the body, and is equipped with a spur gear 5.

My novel sifter also comprises a spring 6, a fixed handle member 7, and an oscillatory handle member 8. The fixed handle member 7 is provided at its inner or forward end with an angularly disposed arm 9 which is arranged alongside of the body 1 and is appropriately fixed in upright position thereto. At the outer or rear end of the fixed handle member 7 the same is provided with an inwardly directed horizontal arm 10 in which is journaled the rear end of the shaft 4. It will also be noticed here that the spur gear 5 is arranged immediately adjacent to the inner side of the arm 10, and that the said arm 10 is provided on its upper edge with a forwardly extending lateral lug 11. The oscillatory handle member 8 is pivotally connected at 12 to the flat inner portion 13 of the handle member 7. At its rear or outer end the said handle member 8 is provided with an inwardly extending arm 14. This arm 14 is toothed at its underside and meshed with the gear 5, and it is arranged between the gear 5 and the before mentioned lug 11 so as to be guided by the latter and held in proper working relation to the gear 5 and this without interfering with free reciprocation of the arm 14. It will also be noticed that the arm 14 is provided near its inner end with an upstanding projection 15 which is designed to bring up against the lug 11 and thereby limit the outward movement of the oscillatory handle member 8 under the action of the spring 6.

It is within the purview of my invention to employ any type of spring designed to be tensioned by inward movement of the oscillatory handle member 8 and to serve for the outward movement of the said handle member 8. I prefer, however, to employ a spring of the type shown, the said spring which is numbered 6 being interposed and supported between the members 7 and 8.

In the practical operation of my novel sifter it will be manifest that when the handle members are grasped in one hand of the operator and the handle member 8 is pressed inwardly against the action of the spring 6 the shaft 4 and the agitator 3 will be sharply turned in one direction, due to the cooperation of the rack on the arm 14 with the spur gear 5 on the shaft 4. When the handle member 8 is relieved of pressure

the spring 6 will operate to press said handle member outwardly which will bring about a sharp turning movement of the shaft 4 and, agitator 3 in reverse direction. Therefore, by simply pressing the handle member, the operator is enabled to sift as much flour or other substance through the screen 2, and this without entailing movement in any direction of the body 1 and without the assistance of the other hand, such other hand being left free for the stirring of the mixture into which the flour or other substance is discharged. It will be apparent from the foregoing that my novel sifter is extremely simple and inexpensive in construction and yet is highly efficient in operation and is not liable to get out of order under ordinary usage.

I have entered into a detailed description of the construction and relative arrangement of the parts embraced in the present and preferred embodiment of my invention in order to impart a full, clear and exact understanding of the said embodiment. I do not desire, however, to be understood as confining myself to the specific construction and relative arrangement of parts inasmuch as in the future practice of the invention various changes and modifications may be made such as fall within the scope of my invention as defined in my appended claims.

Having described my invention, what I claim and desire to secure by Letters-Patent, is:—

1. A flour sifter comprising a cylindrical body, a concavo-convex screen carried in said body, a handle member having an upright arm at its inner end fixed to the said body and also having at its outer end an inwardly directed lateral arm on the upper edge of which is an inwardly extending guide lug, a shaft journaled in the body and in the said

arms of the fixed handle member, an agitator mounted on and arranged to turn with the shaft and also arranged to turn in the body and in close proximity to the upper side of the screen, a spur gear fixed on said shaft and arranged at the inner side of and adjacent to the outer arm of the fixed handle member, an oscillatory handle member pivotally connected to the fixed handle member at a point adjacent to the body and having at its outer end an inwardly directed rack bearing arm intermeshed with the said spur gear, said arm being interposed and movable between the said spur gear and the said guide lug and having a projection at its inner end to spring up against the guide lug and limit outward movement of the oscillatory handle member, and a spring maintained between the handle members.

2. In a flour sifter, the combination of a cylindrical body, a concavo-convex screen therein, a shaft journaled in the body, an agitator arranged in the body and mounted to turn with the shaft, a spur gear fixed on the shaft, a handle member fixed to the body and having a lateral inwardly extending arm on which is a guide lug, an oscillatory handle member pivotally connected to the fixed handle member and having an inwardly directed arm interposed between the guide lug and the spur gear and having a rack intermeshed with the spur gear and also having a projection adapted to bring up against the guide lug and limit outward movement of the oscillatory handle member, and a spring associated with the handle members and arranged to be tensioned by inward movement of the oscillatory handle member.

In testimony whereof I affix my signature.

HARRY NAKAGAWA.
